UNITED STATES PATENT OFFICE.

JOHN A. SHERMAN AND WILLIAM H. SHEPPARD, OF WORCESTER, MASSACHUSETTS;
SAID SHEPPARD ASSIGNOR, BY DIRECT AND MESNE ASSIGNMENTS, OF HIS RIGHT
TO WILLIAM J. WOODS, OF WORCESTER, MASSACHUSETTS.

HEATING PLANT.

Application filed July 8, 1918. Serial No. 243,875.

To all whom it may concern:

Be it known that we, JOHN A. SHERMAN and WILLIAM H. SHEPPARD, both of Worcester, in the county of Worcester and State 5 of Massachusetts, citizens of the United States, have invented a new and useful Improvement in Heating Plants, of which the following is a specification.

The purpose of our invention is to provide 10 a heating plant for household or other use, which in its preferred and complete form is automatic, that is, it will maintain the house at a given temperature during the whole twenty-four hours of the day, or 15 will reduce the temperature temporarily for any predetermined period. This and other features hereinafter described may be carried out by the apparatus shown in the drawings. Certain of the instrumentalities 20 are old and well known in the art, being easily procurable on the market and hence are not described in detail.

In the drawings in which the invention is shown in its preferred form—

25 Figure 1 is an elevation showing the apparatus as a whole diagrammatically.

Fig. 2 is a section of the burner and its feeding tank.

Fig. 3 is an enlarged side elevation of the 30 relay J, and

Fig. 3^a is a front elevation thereof.

Fig. 4 is a side elevation of release switch K.

Fig. 5 is a diagrammatic view in plan of 35 the time switch; and Fig. 6 is a similar view showing the snap switch and its mounting.

A is an oil reservoir of any convenient size, for example, large enough to contain 40 a supply of oil or other liquid fuel capable of lasting say some weeks or months. While we have shown one such tank, the number is purely a matter of convenience. It is provided at A¹ with a suitable opening for filling. A² is a gauge to show the height 45 of oil in the tank.

B is the oil pressure tank which is fed by gravity from the tank A through the pipe a whenever the pressure in tank B is sufficiently low, this tank preferably 50 holding a day's supply of fuel. The pipe a contains a check valve a¹ to prevent the oil in the tank B from backing into the tank A when under pressure.

C is the burner supply tank, which is mounted on the stand C³ and is closed 55 airtight. It is supplied with oil from the tank B by the pipe b. A valve b¹ located in the pipe b may be used to cut off the oil supply to the tank C when desired. The pipe b terminates in a valve c located in said 60 tank C (see Fig. 2) and controlled by the lever c¹, rod c² and float c³, the whole being adjusted to maintain the oil c⁴ in the tank at the desired height, operating after the 65 manner of the ordinary ball cock.

D is the casing of the burner. It has a neck D¹ by which it is supported in an opening in the cover of the tank C. Axially mounted in the casing D is the fuel nozzle d, which has a passage d² running partly 70 through it connected by the opening d⁶ with a longitudinal passage in the neck D¹, which latter passage is connected with the passage in the pipe D² running nearly to the bottom 75 of the interior of the tank C.

The casing D has a jet opening d¹ which registers with the opening d³ in the tip of the nozzle d.

The rear end of the nozzle beyond the opening d⁶ is solid and is threaded and 80 passes outside the rear end of the casing D through a nut d⁴ which is so attached to the casing as to turn thereon and by turning adjust the location of the tip of the nozzle d with relation to the jet opening. A screw 85 d⁵ sets into a longitudinal groove in the nozzle so as to keep it from turning with the nut while adjustment is being made.

The opening d⁶ is sufficiently long to keep in register with the opening in the neck 90 D¹ however the nozzle may be adjusted.

Between the casing D and the nozzle d is an air chamber f¹ which surrounds the sides of the nozzle and its tip and is supplied with compressed air by the pipe f 95 which leads into it from the air pump F. The oil is drawn up from the tank C by suction due to the passing out of the compressed air from the chamber f¹ through the opening d⁴ and past the tip d³ of the nozzle, 100 the whole acting after the manner of an atomizer.

A passage f² leads from the chamber f¹ to the tank C and supplies air under pressure to the surface of the oil in the tank 105 so as to assist in lifting the oil to the nozzle

as well as to supply the place of the oil as it is withdrawn. By adjusting the nozzle longitudinally as above described the amount of the oil feed will be adjusted in 5 the well known way.

E is the casing of the firebox of the heater and it is provided with a door E¹ in which an opening is located registering with the opening d¹ in the end of the burner casing so that the flame from the burner will be thrown into the firebox (see Fig. 2). E² is the covering for a peep hole by which the flame may be inspected and e is a pilot light mounted on the outside of the firebox 10 near the burner D and connected to the gas supply of the burner.

The air pressure in the tank C will balance the pressure in the tank B so that the oil will flow from B to C by gravity. The 20 pressure in the tank B will prevent oil from flowing from A to B except when that pressure is reduced sufficiently, for example, when the pump F is idle.

The oil is thus drawn from the tank C 25 to the burner by compressed air acting chiefly by suction so that the more pressure given to the air, the better vacuum is created and the more oil is sucked up. It has been found that under usual conditions 30 more perfect combustion is secured in this way when the parts D and d are properly adjusted with relation to each other, the air determining the amount of flame thrown into the firebox.

35 An additional advantage of this construction lies in the fact that when the air pressure is shut off, the oil settles back from the burner into the tank, thus avoiding any leakage or overflow of oil into the firebox.

40 Compressed air is supplied to the pipe f by the air pump F operated by the electric motor G. The pipe f runs from the air pump to the coupling F¹ from which it supplies pressure to the oil in the oil pressure tank B and from thence to the casing D and also to the tank C by the passage f² as 45 above described. Thus the flame is controlled by the air pressure at the burner, which sucks up the oil into the burner and atomizes it, and the air pump F which gives this pressure is controlled by the motor G. The stoppage of the motor, therefore, momentarily or otherwise, stops the supply of fuel so that the flame is extinguished. To 50 relight it the pilot burner e is preferably used.

The motor G as shown is in a loop from the main electric circuit of the house independent of the lighting circuit and its 60 circuit is controlled by a thermostat located in any desired part of the house, say the living room or hall, the arrangement being such that when the house temperature has reached a predetermined high degree the 65 motor circuit is broken so that the motor

stops, thus stopping the pump and the fuel supply to the burner. When the temperature has dropped to a predetermined degree, the circuit is again closed and the motor starts up the pump to feed fuel to 70 the burner, its fuel being ignited by the pilot light.

The house or main circuit is indicated in the drawings by the wires X and Y. The motor G takes its current from one of 75 these wires, say wire X, by the wire 1. The return wire 2 from the motor is connected to a bracket 3 mounted on base 300 of insulating material at the relay J. The electro-magnet 15 of the relay is operated 80 automatically by a circuit including the thermostat H, as will be explained later.

The relay comprises the electro-magnet 15 which has an armature 17 pivoted at 152 to a bracket 181 and terminating in a latch 171 which normally engages and holds up a lever 18, also pivoted to the bracket 181 mounted on the base 300, but electrically insulated from said bracket as indicated by washers 182 in Fig. (3^a). This lever 18 is 90 slotted and is normally held in the position shown in Fig. 3 by the latch 171 at the end of the armature 17 against the force of a spring 19 attached to it and the support 3 which passes through the slot in the 95 lever 18. The attraction of the armature 17 by the energization of coil 15 will lift the latch 171 from engagement with the lever 18 and the spring 19 will throw the lever 18 out so that the latch 171 and lever 100 and springs 19 and support 3 become separated, thus breaking the circuit at this point.

The circuit is normally by wire 2 to bracket 3, expansion spring 19, lever 18, latch 171, bracket 181 and wire 4 to the 105 release switch K. The wire 4 is attached to the bracket 181 through the base 300 in any convenient way.

The relay J is controlled by a thermostat H of usual construction in circuit with the 110 electro-magnet 15. Its thermostatic arm 10 is connected directly by wire 9 with the main wire X. Two terminals 11 and 20 are provided, with either of which the arm 10 may engage, or, as shown in Fig. 1, it 115 may be in neutral position as when the temperature is at the desired normal degree, say 69°. When the temperature rises to say 70° or any other point for which the arm is set, the circuit is closed through the 120 arm 10 to the contact 11 and by the wire 12 through a time switch 13 of ordinary construction, wire 14, to the coil 15 of the electromagnet, from whence this circuit proceeds through the wire 16 to the main line Y. 125

The energizing of the coil 15 attracts the armature 17 so that the latch 171 releases the lever 18 and allows the spring 19 to push out the lever 18, thus breaking the motor circuit and causing the motor to stop 130

and stop the pump, cutting off the supply of oil from the burner at the boiler.

As the house becomes cooler the arm 10 resumes its neutral position and then moves 5 over until it makes contact with 20 thus establishing the circuit from line X through wire 9, arm 10, contact 20, wire 21, time switch 13, wire 22, to coil 23, thence by wire 24 to the main line Y. The lever 18 acts as an armature to be attracted by the coil 23 and hence, when this coil is energized, the lever 18 is attracted and the parts 117 and 18 re-engage, thus re-establishing the main circuit from the relay J by wire 4, release switch K, wire 6, etc. to the main line Y, so that the motor is again energized, starting up the pump and the oil circulation.

If after the motor circuit has been broken it is again closed as above described the pilot light relights the fuel at the burner. If, however, the pilot light has accidentally been extinguished, while the burner will again be supplied with fuel, the fuel will not be ignited, but will flood the firebox which will be cooling off. The main purpose of the release switch is to give an alarm under such conditions. It comprises a base 400 of insulating material on which is mounted a switch 5 normally engaging the switch point k^1 to which wire 4 is connected. This switch 5 is of usual knife blade construction and is hinged at k to a conducting member mounted on the base 400 and electrically connected with the wire 6 which runs to a snap switch 7 and is continued by wire 8 to wire Y of the house circuit.

On the base 400 is also hinged an armature 34 controlled by an electro-magnet 32. Against this armature 34 rests a circuit controller 35 on one end of an insulated push rod 351 which rod is slidable through the base 400, its other end contacting with the free end of the switch 5. Upon the energizing of the coil 32 the armature 34 is attracted, thus releasing the controller 35 and allowing a spring k^2 , one end of which is attached to the controller and the other end connected to the base 400, to pull the controller 35 toward the base 400, thus causing the push rod to push switch 5 out from its contact with k^1 into the position shown in dotted lines in Fig. 4 and breaking the circuit.

At the same time 35 makes contact with terminal 361. This terminal is connected by wire 36 with an alarm bell N which is also connected by wire 37 with the main line X. The controller 35 being connected by wire 38 with the main line Y, when 35 comes in contact with the point 361 a circuit is closed through the bell and the bell rings.

The coil 32 is in circuit with a thermostat P controlled by the temperature in the firebox. It comprises a thermostatic arm 26

which is connected with the main line X by the wire 25 and a contact 27 arranged in such a manner that when the temperature gets below a certain point due, for example, to the accidental extinguishing of the pilot 70 light, the arm 26 will make contact with contact 27. The contact 27 is connected by wire 28 with a terminal 29 adapted to contact and normally contacting at the compressed air motor R with a terminal 30. 75 This terminal 30 is connected by wire 31 with coil 32, the lead 33 from which connects with the main line Y, so that when the circuit is closed at 26 and 27 and at 29 and 30 coil 32 will be energized, its armature 80 attracted, and switch 5 thrown out by the release of circuit closer 35, thus breaking the motor circuit and ringing the alarm bell.

The parts will remain in this condition holding the motor circuit open at this point 85 until the member 5 is reset by hand, but this cannot be done because so long as the circuit through the coil 32 is closed its armature will be attracted and the rod 351 will prevent the resetting of the switch 5. 90 To break this circuit quickly the contacts 29 and 30 are provided, the position of one of which, say 30, is controlled by pressure in the air system. This contact 30 is mounted on, and insulated from a rod q^1 carried by 95 a spring diaphragm q which closes the end of a compressed air cylinder Q, this cylinder being connected by a feed pipe q^2 to the pipe f of the compressed air system. This construction is such that when the air in the cylinder Q is under full pressure its diaphragm q serving as a compressed air motor is convexed and 29 and 30 are in contact, and when under less pressure it is concaved and the contacts 29 and 30 are 100 separated, thus breaking the circuit through coil 32 (see Fig. 1.). Q² is a throttle valve by which the admission of air pressure to the cylinder Q may be controlled so that pressure in cylinder Q will accumulate 105 slowly. Thus when 29 and 30 have been separated by the release of pressure in cylinder Q it will take an appreciable time after the starting up of the air pump to bring them again into contact, during which 110 time the burner having been ignited will warm the firebox and separate arm 26 from 27.

When the air pump stops owing to the breaking of the motor circuit, air pressure 120 will leak from the whole compressed air system through the burner, thus causing the separation of 29 and 30. When originally starting the system, the pilot light is lighted and the motor is connected with the source 125 of current, after which the apparatus operates automatically until the pilot light is accidentally or intentionally extinguished.

The snap switch which is connected by wire 6 with the release switch K and by

the wire 8 with the house circuit wire Y, breaks the circuit when the boiler pressure is too great. It is constructed and operated as follows: The switch is mounted on a 5 base plate 81 of insulating material. It comprises two independent arms 74 and 75 both of which are pivoted at 71 to the base plate 81. 72 is a spring which is connected to each of these arms in such a manner as 10 to hold them normally at a slight angle to each other as shown in Fig. 1. A rod m^2 connects the arm 74 with the free end of lever m , the other end of the lever being pivotally supported on the pressure motor 15 M. This lever rests upon a rod m^1 connected to a diaphragm (not shown) in the pressure motor M. Such a motor is of well known construction such that the diaphragm within it is raised when the pressure in the 20 boiler rises above a certain amount. The diaphragm lifts the rod m^1 , lever m and the rod m^2 and pushes up the arm 74. This carries the spring 72 over the centre 71 so that it pulls the arm 75 off its contact 73, 25 thus breaking the connection with the wire 8 which forms the return circuit to wire Y. Thus when by any accident the pressure in the heater or boiler has exceeded the safety point, the motor circuit will be opened and 30 the motor will be stopped, thus extinguishing the flame of the burner and allowing the boiler pressure to lower when the snap switch will be reset. This switch will be reset automatically by the lowering of pressure in the boiler and the pressure motor. 35

We have shown in Fig. 5 diagrammatically what we have termed a time switch containing a second thermostat. This second thermostat is in all respects like the 40 thermostat H, but it is adjusted so that it operates between lower temperatures than the thermostat H, but it is connected to elements whereby it is made operative or thrown into circuit only at predetermined 45 periods of time, and at other times it is ineffective, as described below. Thus during the day thermostat H may be used in which the range of temperature may be say between 68 and 70°, while the time switch 50 at say 10 o'clock at night, or at any other desired time, may switch off this thermostat and switch in another thermostat the range of which may be between 40 and 42°, which thermostat will be kept in circuit until say 55 5 o'clock in the morning when the day thermostat will be again switched in, to raise the temperature and keep it during the day at substantially normal house temperature. This time switch will be understood from 60 Fig. 5 in which it is shown diagrammatically. On the base 13, which is of insulating material, is mounted a cam wheel 131 which is preferably rotated by clockwork making a single rotation in any desired 65 time, say 24 hours. Its swell is so con-

structed as to correspond with the proportion of the day or other period during which its thermostat is to be effective. A lever 132 pivoted at 133 carries a finger 134 adapted to rest on the edge of the cam, 70 being held against it by the spring 135 one end of which is attached to the arm 132 and the other end to the base 13. The outer end of this lever carries a contact 136. It also carries an arm 137 which is insulated from 75 it, but also carries a contact 138. The wire 21 is connected to two contacts, one of which 139 is positioned to receive the contact 136 and the other 231 to receive the contact 138. The wire 21 runs back to the contact 20 in 80 thermostat H. This contact is the one which the thermostatic arm 10 strikes when the temperature is below normal. The wire 22 is connected to the arm 132 so that when the cam is in the position shown, i. e. during 85 the daytime and the temperature causes contact between 10 and 20, the circuit is from line x, through wire 9, arm 10 and contact 20, line 21, through contacts 139, 136, lever 132, wire 22 to the relay. When the arm 10 90 is caused by the temperature to contact with the contact 11 the circuit is from x by wire 9 and arm 10 to contact 11, wire 12 and wire 14 to the relay J without including the operative parts of the time switch. When 95 the cam has turned so that its swell lifts the lever 132 contact is broken between 136 and 139 and is made between 138 and 231. This switches into the circuit between 9 and the relay J the second thermostat 233, etc. 100 which controls the temperature between say 40 degrees and 43 degrees or whatever temperature the second thermostatic arm 233 is adjusted to. Thereafter the temperature in the house cannot rise above say 42 degrees 105 because this second thermostat will cause the motor circuit to be broken when this degree of temperature is reached. The first thermostat H in this case becomes part of the closed circuit between the wire 9 and the 110 arm 233 of the second thermostat 234 and the second thermostat is cut out of circuit when the cam 131 allows contact to be made again between 136 and 139. The arm 235 contacts with contact 236 at the lower 115 temperature and with contact 237 at the higher temperature. Thus the time switch may be so set that during the night the motor circuit is controlled by the temperature just as in the daytime, but the temperature is 120 controlled between different limits. The cam may be geared to the clock to operate in longer periods than 24 hours, for example, so that a house may be left over a weekend without danger of the water pipes 125 freezing or the fuel being wasted, the shifting of the thermostats being adjusted so that the house will be warm when the occupant returns. Of course such a time switch may be constructed to operate at desired 130

times according to the requirements of the situations and circumstances under which it is used.

The motor circuit can be traced from the house wire X by wire 1 to the motor G, thence by wire 2 to bracket 3, spring 19, lever 18, latch 171, bracket 181, wire 4 to the release switch member 5, thence by wire 6 and snap switch pivot 71; arm 75, contact 73 and wire 8 to return wire Y. This line is broken when the thermostat H or the thermostat in time switch 13 closes the circuit through the wire 14 which leads to electromagnet 15 and by wire 16 to the return wire Y, in which case the armature 17 is attracted and moves the latch 171 so that it releases the lever 18 which is pushed out by the spring 19. This it will be seen breaks the motor circuit at 171 and 18. The lever 18 is again reset by the operation of the thermostat closing the circuit through 22, electromagnet 23 and wire 24 which is a return to the wire Y.

If the pressure in the boiler be too great the snap switch operates to open the circuit at 73, 75, and if the pilot light goes out, the circuit is closed at 26 and 27 in which case the circuit is from wire X by 25 to the thermostat arm 26, contact 27, wire 28, contacts 29 and 30, wire 31, electromagnet 32 and return wire 33 to wire Y. 29 and 30 will be in contact so long as the air pressure is held in the air system by the motor or otherwise and will be thrown into contact when the air pressure supplies air to the container Q under sufficient pressure to bulge the diaphragm q outwardly as above described. When the thermostat P at 26 and 27 closes the circuit electromagnet 32 attracts the armature 34, releasing the catch 35 and breaking the circuit between the switch k¹ and its contact 5 and at the same time making contact between 35 and 36 in the bell circuit which comprises the wires 37, 38, thus ringing the bell N.

The system is thus automatically controlled by controlling the motor circuit, for it will stop the motor:—

First. When the house is too hot, causing it to start up again when the house cools again to a predetermined degree.

Second. When the boiler pressure has exceeded a certain limit, and start it when the pressure has gone down.

Third. When it is desired to keep a lower temperature for a given length of time, say during the night or for a day or more if absent from the house for a visit, after which the motor circuit is closed again.

Fourth. It will also give an alarm when the pilot light is out or the supply of oil is exhausted so that the burner cannot supply flame to the firebox.

Other means to carry out our invention will occur to those skilled in the art.

What we claim as our invention is:—

1. In a heating system, a burner, an air pump, and connections whereby said pump will supply fuel to said burner, and electrical means for operating said pump comprising an electric motor and a circuit therefor comprising a source of current and a relay-operated switch, a latch normally engaging said switch to hold it in closed position, an electro-magnet adapted when energized to disengage said latch from said switch, and a second electro-magnet adapted when energized to rest said switch, and thermostat circuits each containing one of said electro-magnets, said thermostat circuits also comprising a single thermostat arm whereby when said thermostat is under the influence of a predetermined degree of heat said arm will close the circuit through said latch-disengaging electro-magnet, whereby said motor circuit will be broken and when said arm is under the influence of a predetermined degree of cold it will close the circuit through the second electro-magnet whereby said switch will close said motor circuit and said latch will re-engage said switch.

2. In a heating system, a burner, an air pump, and connections whereby said pump will supply fuel to said burner, and electrical means for operating said pump comprising an electric motor and a circuit therefor comprising a source of current and a relay-operated switch, a latch normally engaging said switch to hold it in closed position, an electro-magnet adapted when energized to disengage said latch from said switch, and a second electro-magnet adapted when energized to reset said switch, and thermostat circuits each containing one of said electro-magnets, said thermostat circuits also comprising a single thermostat arm whereby when said thermostat is under the influence of a predetermined degree of heat said arm will close the circuit through said latch-disengaging electro-magnet, whereby said motor circuit will be broken and when said arm is under the influence of a predetermined degree of cold it will close the circuit through the second electro-magnet whereby said switch will close said motor circuit and said latch will re-engage said switch.

3. In a heating system, a burner, an air pump, and connections whereby said pump will supply fuel to said burner, and electrical means for operating said pump comprising an electric motor and a circuit therefor comprising a source of current and a relay-operated switch, a latch normally engaging said switch to hold it in closed position, an electro-magnet adapted when energized to disengage said latch from said switch, and a second electro-magnet adapted when energized to rest said switch, and a heater comprising a firebox located to be heated by said burner, and a heater pressure motor adapted to be operated by changes of pressure in the heater, said motor circuit also comprising a second switch normally closed and operable by said pressure motor whereby when the pressure in said heater exceeds a predetermined amount said pressure-operated switch will be opened to open said motor circuit and thus cause the stoppage of the pump and the feeding of fuel to the burner.

3. In a heating system, a burner, an air pump, and connections whereby said pump will supply fuel to said burner, and electrical means for operating said pump comprising an electric motor and a circuit therefor comprising a source of current and a relay-operated switch, a latch normally engaging said switch to hold it in closed position, an electro-magnet adapted when energized to disengage said latch from said switch, and a second electro-magnet adapted when energized to reset said switch, and thermostat circuits each containing one of said electro-magnets, said thermostat circuits also comprising a single thermostat arm whereby when said thermostat is under the influence of a predetermined degree of heat said arm will close the circuit through said latch-disengaging electro-magnet, whereby said motor circuit will be broken and when said arm is under the influence of a predetermined degree of cold it will close the circuit through the second electro-magnet whereby said switch will close said motor circuit and said latch will re-engage said switch, in combination with a heater comprising a firebox located to be heated by said burner, and a heater pressure motor adapted to be operated by changes of pressure in the heater, said motor circuit also comprising a second switch normally closed and operable by said pressure motor whereby when the pressure in said heater exceeds a predetermined amount said pressure-operated switch will be opened to open said motor circuit and thus cause the stoppage of the pump and the feeding of fuel to the burner, and when the pressure in the heater has been reduced below said predetermined amount said pressure-operated switch will again be closed, and said pump become operative.
4. In a heating system, a firebox, a burner located to heat it, an air pump and connections whereby said pump will supply fuel to said burner, electrical means for operating said pump comprising an electric motor and a circuit therefor comprising a source of current and a release switch and means for throwing said release switch to break said circuit comprising an electro-magnet and a circuit therefor including a thermostat located to be operated by the temperature of the firebox, said thermostat normally opening said electro-magnet circuit but adapted when the temperature of the firebox goes below a predetermined degree to close said electro-magnet circuit whereby said electro-magnet will be energized and cause said release switch to be thrown to open said motor circuit.
5. In a heating system, a firebox, a burner located to heat it, an air pump and connections whereby said pump will supply fuel to said burner, electrical means for operating said pump comprising an electric
- motor and a circuit therefor comprising a source of current and a release switch and means for throwing said release switch to break said circuit comprising an electro-magnet and a circuit therefor including a thermostat located to be operated by the temperature of the firebox, said thermostat normally opening said electro-magnet circuit but adapted when the temperature of the firebox goes below a predetermined degree to close said electro-magnet circuit whereby said electro-magnet will be energized and cause said release switch to be thrown to open said motor circuit, in combination with a circuit closer located in said electro-magnet circuit, and means comprising a compressed air motor, and connections with said air pump, whereby when said motor circuit is closed said pump will be energized and will energize said air motor and cause it to bring one member of said circuit closer into contact with the other member and maintain them in contact.
6. In a heating system, a firebox, a burner located to heat it, an air pump and connections whereby said pump will supply fuel to said burner, electrical means for operating said pump comprising an electric motor and a circuit therefor comprising a source of current and a release switch and means for throwing said release switch to break said circuit comprising an electro-magnet and a circuit therefor including a thermostat located to be operated by the temperature of the firebox, said thermostat normally opening said electro-magnet circuit but adapted when the temperature of the firebox goes below a predetermined degree to close said electro-magnet circuit whereby said electro-magnet will be energized and cause said release switch to be thrown to open said motor circuit, in combination with a circuit closer located in said electro-magnet circuit, and means comprising a compressed air motor, and connections with said air pump, whereby when said motor circuit is closed said pump will be energized and will energize said air motor and cause it to bring one member of said circuit closer into contact with the other member and maintain them in contact.
7. In a heating system comprising a burner, a firebox and electrically-controlled means for supplying fuel to said burner including an electric circuit, a release switch in said circuit, means for operating said release switch comprising a rod, an electrically-operated alarm, a circuit therefor normally open, a circuit closer, one terminal thereof being connected to said rod to be operated thereby when said rod is released,

- a latch adapted to hold said rod normally in retracted position whereby said release switch will remain closed, and means for operating said latch comprising an electro-
5 magnet and a circuit therefor including a thermostat adapted to close said electromagnet circuit when said firebox is cold whereby when fuel is not ignited at the firebox said rod will operate said release
10 switch and will also cause the closing of said alarm circuit to operate said alarm.
8. In a heating system, an air pump, an electric motor connected thereto, a circuit for said motor comprising a relay-operated
15 switch having two coils, a thermostat circuit comprising a heat-controlled arm and two terminals, each terminal being connected to one of said coils whereby the contact of said thermostat arm with one
20 of said terminals will close the circuit through one of said coils and open the relay-controlled switch in said motor circuit and the contact of said thermostat arm with the other of said terminals will close the circuit
25 through the other coil and close the relay-controlled switch in said motor circuit, in combination with a time switch located in said thermostat circuit and adapted to cut out said thermostat from said circuit for
30 a predetermined period of time and substitute for said predetermined period means for opening and closing said motor circuit having ranges of temperature different from those of said thermostat.
- 35 9. The heating system above described comprising a boiler, a fire box therefor, a burner to heat said fire box and means for lighting said burner, electrically-controlled means for supplying fuel to said burner comprising an electric motor, a circuit therefor and an air pump operated by said motor, two circuit breakers located in said circuit, one comprising a thermostat adapted to break the circuit when the temperature exceeds a predetermined degree and the other comprising a switch and a pressure valve connected to said switch to operate it and located to be operated by the pressure in the boiler when said pressure exceeds a certain amount to move said switch to break its circuit whereby said circuit may be broken by excess of temperature or by excess of boiler pressure.
10. The heating system above described comprising a firebox, a boiler to be heated from said firebox, a burner and means for lighting it, electrically-controlled means for supplying fuel to said burner comprising an electric motor, a circuit therefor and an air pump operated by said motor and thermostatic means adapted to open and close said motor circuit, and means for opening said motor circuit when said lighting means is operative comprising a pressure motor located to be operated by the pressure of said boiler, a switch located in said motor circuit and connections between said pressure motor and said switch whereby any excess of pressure in said boiler will cause said pressure motor to operate said switch to open said motor circuit.
